(57) **CLAIM**

The ornamental design for a vehicle wheel with three dual spokes, as shown and described.

DESCRIPTION

FIG. 1 is a perspective view of the front or outer side of a vehicle wheel with three dual spokes according to my invention. The inner or rear side of the wheel is identical to the front side and the outer ends of all spokes are identical; and,

FIG. 2 is a cross-sectional view of the wheel of FIG. 1 taken along the lines 2—2 of FIG. 1.
